UNITED STATES PATENT OFFICE.

LUDWIG W. STETTNER, OF OAKLAND, CALIFORNIA.

ACETYLENE GENERATOR.

Application filed November 28, 1925. Serial No. 71,902.

My invention has for its object an acetylene generator adapted to employ carbide and control the mixing thereof with water to secure the chemical reaction from which is developed acetylene and to control the chemical action so as to secure a relatively constant rate of acetylene generation corresponding with any fixed rate of discharge and to vary the rate of acetylene generation 10 to compensate for variations in demand, and thus to maintain a relatively constant pressure of acetylene in the said generator and delivery pipes therefrom.

A further object of my invention is a device of the character described wherein the several operations necessary in charging and operating are performed with the greatest safety and reliability.

Another object is special improvements in 20 those portions of the generator apparatus adapted to automatically feed the carbide to meet the demands for gas generation.

Other objects will appear from the drawings and specifications which follow.

25 Referring to the drawings:

Fig. 1 is a prospective side view of the generator of my invention.

Fig. 2 is a fragmentary cross section 30 through certain parts of the upper portion of the generator of Fig. 1, to better show the carbide feeding mechanism.

Fig. 3 is a fragmentary plan view of the top of the generator of Fig. 2.

Fig. 4 is a fragmentary, somewhat diagrammatic view showing certain of the operating parts of Fig. 1, showing particularly the interfering device to prevent improper operation.

40 Fig. 5 illustrates a pressure diaphragm actuated by the pressure of acetylene generated to control the motor.

Figs. 6 to 10 inclusive are details of the carbide feeding mechanism, whereby the carbide is fed from the table member into the water at a rate proportional to the requirements, Fig. 6 being a plan view, Fig. 7 a side elevation, Fig. 8 a plan view with the carbide distributing mechanism in place under the table and Figs. 9 and 10 end views 50 showing the operation of the carbide fingers.

Fig. 11 is a detailed showing of the starting, stopping and controlling connections between the diaphragm of Fig. 5 and the motor 3 of Fig. 1.

55 Throughout the figures similar numerals refer to identical parts.

A generator casing is shown by the numeral 1 closed on the top and bottom and provided with a residuum drain valve 2, a clock work motor 3, actuated by a weight 4, 60 a driving shaft 96, actuated by the said clock motor, a carbide hopper 6, a filler cap 7, by which carbide is introduced into the hopper, a carbide feeding table 8, fingers 45, and 46 are actuated from the drive shaft 96, 65 a condensation shield 9, adapted to keep any condensed moisture clear of the feeding table, so that the carbide thereon is kept relatively dry, a carbide guard ring 10 which serves as a screen to prevent or permit the 70 discharge of carbide from the table 8, a water filler 11, communicating with the interior of the casing 1, through the water cock 12 and pipe 13, an overflow cock 14 adapted to limit the water level at 15 in the casing 1, an overflow outlet 16, an overflow plug at 17, a chamber at 18 to prevent flashback, 75 a pressure gauge at 19 to indicate the pressure existing at all times within the casing 1, a safety valve at 20, with a blow-off lever controlled valve at 21, and a similar safety valve and blow-off lever valve at 22 and 23 respectively, a main service cock 24, a handle at 25 mounted on the operating stem 26, the 80 said stem having a motor lock and release arm at 27 and filler cap shield 28, a link 29 adapted to actuate the levers 21 and 23 of the safety valves 20 and 22 respectively, a second stem at 30 actuating the residuum valve 2 and the overflow cock 14 during a portion 85 of the movement of the handle 25, a stirring member 39, a guard ring operating lever at 31 on the worm shaft 32 adapted to actuate the carbide guard ring 10 and when the ring is in the up position the lever 31 covers the cap 7 to prevent filling until the ring has been depressed by swinging the lever 31 90 from the full line to the dotted position of Fig. 3, in which position it locks the motor 3. 95

Referring to Figs. 1, 3 and 4—the lever 25 is fixed to the stem 26 and is provided with an arcuate slot 75 in which engages the pin 76 carried on the yoke 77. This yoke 77 is fixed with the secondary stem 30 which is adapted to actuate the drain valve 2.

100 Upon the first movement of the lever 25 from the position of Figs. 1 and 3 outward, the stem 26 is actuated shifting the link 29 and opening to the atmosphere the valves 21 and 23, and shifting the cap shield 28 110 clear of the cap 7 and causing the arm 27 to engage and lock the motor 3 by any con-

ventional means, well-known but not specifically shown. The further movement of the lever 25 causes the arcuate slot 75 to pick up the pin 76 swinging the yoke 77 and opening overflow valve 14 and freeing the discharge valve 2. On reversing the movement of lever 25, the valve 2 is first closed after which the other reverse movements take place in the reverse order, the valves 21 and 23 being the last to be closed.

A main gas discharge is shown at 82 under the control of the service cock 24 and from which the acetylene generated is delivered, control connections at 33 and 34 are adapted to start, stop and control the rate of movement of the said motor and connected at their lower end with a diaphragm device 35 actuated by pressure from the casing 1, whereby an increase of pressure in the said casing retards the motor and a decrease of pressure in the said casing allows the motor to speed up under the actuation of the weight 4. This is accomplished by any well known mechanism.

The diaphragm is indicated at 36, Fig. 5. Referring to Fig. 2, the carbide is held in hopper 6 which has been fitted through filler cap 7. The guard ring 10 is under the control of the shaft 32 the rotation of which is adapted to raise and lower the said ring through the action of a worm member 70, and arms 71, 71. A plurality of these worms and arms may be employed to better support and operate the said ring being interconnected for joint operation, such construction is conventional forming no part of my invention and is not shown in detail, it being understood that any conventional raising and lowering means may be employed to actuate said ring from the movement of the external lever 31.

Referring particularly to Figs. 6 to 10, the table 8 is a rigid member on which the carbide charge normally rests, being fed down thereon so as to continually maintain the table charged from the hopper 6.

The rotating stem 96 passes down through the stationary tube 78 and cone member 40 and table 8 and rotates the arm 41 from the clock or motor mechanism at 3 at a rate of speed controlled from the diaphragm device above mentioned and as shown in detail in Fig. 5, through the conventional connections 33 and 34.

Upstanding from the arm member 41 are the pivoted pedestals 42 and 43 and through the upper portion of these pedestals is rotatably swivelled the members 44 and 65 having finger extensions 45 and 46 respectively which extend from below and over the top of the table 8 and during the rotation of the shaft 96 are forced to travel around the table with the finger extensions engaging and raking off of the table the carbide to be fed into the water in container

1 in proportion to the demand for acetylene gas to be generated.

These swivelled finger members, as the arm 41 rotates, engage on their inner ends the depending pins as 47 and 48 and are thereby tripped and the members 42 and 43 are thereby forced to pivot on the arm 41.

The fingers 45 and 46 are therefore caused to follow the dotted paths 49 and 50 respectively on the table 8 (see Fig. 6).

After the arms 44 and 65 ride clear of the pins 47 and 48 the weights 59 and 59 dropping from the position of Fig. 9 to the position of Fig. 10 cause the members 44 and 65 to swing the fingers 45 and 46 towards the center of the table.

This movement is occasioned through the weight 59 pivoted at 51 and carrying the U member 52 through which are arm projects, to actuate the arm from the position of Fig. 9 to the position of Fig. 10, swinging the fingers 45 and 46 from the position in Fig. 6 as shown by the dotted paths 60 and 61 respectively towards the center and jarring or shaking loose the carbide if it is packed and preventing any bridging of the carbide as well as engaging masses of carbide which are thereby raked off of the table 8 during the further movement.

On the top of the pedestals 42 and 43, I provide rollers 62 and 63 to better maintain the alignment of the arm 41 and spacing of the finger members 45 and 46 over the table 8.

The operation is as follows:

The operating stem 26 is rotated by 100 pulling outward the handle 25 and opening the valves 22 and 23 to the atmosphere.

The water cock 12 is now opened by pulling its lever forward.

The rotation of the stem 26 has shifted 105 the cap shield 28 away from the filler cap 7. The lever 31 is now rotated also uncovering the cap 7 and its movement continued into the locking position shown by dotted lines in Fig. 3. This movement has rotated the 110 worm shaft 32 and dropped the carbide guard ring 10 substantially to the feeding table 8.

The charge of carbide is now introduced into the carbide hopper 6, the cap closed 115 and water is introduced into the filler cup 11 until it overflows at the outlet 16, having passed through the overflow cock 14.

The lever of the water cock 12 and the lever 25 of the operating stem 26 are actuated, the blow-off or safety valves 20 and 22 are now open, the lever 31 restored to its full line position of Fig. 3 raising the carbide guard ring 10 so that the carbide is now ready to be fed from the table 8 into the 125 water in the lower part of the casing 1.

The motor lock arm 27 has been swung out by the movement of the stem 26 and the motor mechanism is started whereupon the feeding mechanism (see Figs. 7 and 10 in- 130

clusive) is now set into movement and the fingers rake carbide from the table 8 which, falling into the water, generates acetylene gas which, collecting in the upper part of the casing, establishes a pressure under the diaphragm 36 of Fig. 5 until the diaphragm has raised a sufficient amount to retard or stop the motor 3 or until the acetylene is withdrawn from the discharge pipe 82. After all the air is blown out of the container 1, the valves 21 and 23 are closed by a final movement of lever 25 to the full line positions of Figs. 1 and 3. This blowing out of the air is accomplished by the acetylene being generated in the container 1, the air is now discharged through the pipe 97, which is tapped into the highest point of the container 1 and passes out through the safety valve 22, because of the cock 23 being open. Any reduction in the gas pressure results in a dropping of the diaphragm of Fig. 5 and an acceleration of the feeding mechanism while any increase in pressure acts conversely resulting in a retarding in the feeding mechanism whereby the carbide feeds from the table 8 into the water and therefore the rate of acetylene generation is retained directly proportional to the requirements of gas consumption from the discharge to the tube 32.

I claim:

1. In an acetylene generator having there-

in a water compartment and thereover a carbide hopper, a fixed table spaced under said hopper adapted to support carbide, an arm rotatable under said table, finger means carried by said arm and projecting over said table constructed and adapted to progressively rake the carbide from the table to fall into the water as the arm rotates and including a finger adapted to engage portions of the carbide and a stem carrying said finger and swivelled to said arm and restoring means engaging said stem to force the finger to engage the carbide. 45

2. In an acetylene generator having there-
in a water compartment and thereover a carbide hopper, a fixed table spaced under said hopper adapted to support carbide, an arm rotatable under said table, finger means 50
carried by said arm and projecting over said table constructed and adapted to progressively rake the carbide from the table to fall into the water as the arm rotates and including a finger adapted to engage portions of the carbide and a stem carrying said finger and swivelled to said arm and restoring means engaging said stem to force the finger to engage the carbide, a plurality of 55
fixed trip members against which said stems engage during the rotation of said arm and are thereby swivelled to actuate said finger movement. 60
